US00D586236S

(12) **United States Design Patent**
Madsen et al.

(10) **Patent No.:** **US D586,236 S**
(45) **Date of Patent:** **** Feb. 10, 2009**

(54) **CLOCK**

(76) Inventors: **Jesse Madsen**, 3762 Glen Park Rd.,
Oakland, CA (US) 94602; **Jarret Cuisinier**, 648 Guerrero St., San
Francisco, CA (US) 94110

(**) Term: **14 Years**

(21) Appl. No.: **29/308,885**

(22) Filed: **Jul. 14, 2008**

(51) LOC (9) Cl. **10-01**

(52) U.S. Cl. **D10/7; D10/15**

(58) Field of Classification Search **D10/1-29;**
D21/578, 611; D14/189; 368/276, 285,
368/316, 29, 30, 82-84, 250

See application file for complete search history.
